DESCRIPTION

U.S. PATENT DOCUMENTS

FIG. 1 is a perspective view of a tread portion of an automobile tire;

D505,384 S * 5/2005 Kageyama D12/567
D526,954 S * 8/2006 Godeau D12/539
D550,147 S * 9/2007 Radulescu D12/545
D563,861 S * 3/2008 Foucher D12/560
D627,707 S * 11/2010 Le et al. D12/566

FIG. 2 is a front view thereof, wherein top, bottom and rear views are identical and thus omitted;

FIG. 3 is a left side view thereof, wherein the right side view is identical and thus omitted;

FIG. 4 is a fragmentary enlarged view showing the details of the tread portion thereof; and,

FIG. 5 is an end view taken along line A-A in FIG. 4.

In the drawings, the broken lines defining the sidewall and the inner bead of the tire depict environmental subject matter that forms no part of the claimed design.
